DRAINAGE LEAF ATTACHMENT MEANS FOR
LEAF TYPE FILTERSReinier P. De Vries, Melrose, Mass., assignor to
Revere Sugar Refinery, Boston, Mass., a corporation of Massachusetts

Application October 25, 1950, Serial No. 192,075

1 Claim. (Cl. 210—195)

1

This invention relates to improvements in drainage leaf structures for filters of the leaf type.

In filters of the Sweetland type, it has heretofore been the practice to attach each drainage leaf to the stationary upper body section of the filter by means of an endwise open or tubular outlet nipple adapted to be threaded into an outlet spud which is welded to a sheet metal outlet stamping to which the sheet metal binding or frame of the drainage leaf screen is likewise welded. The side walls of the outlet nipple are provided with discharge openings, which communicate through suitable connections with the filtrate manifold of the filter. The outer open end of the outlet nipple is closed by a cap nut which screws onto the exteriorly projecting upper end of said nipple, which cap nut also serves as the means for affixing the nipple to the upper body section of the filter so as to suspend the drainage leaf attached thereto within the interior of the filter body. Attachment nipples so constructed and secured to a drainage leaf and to the upper body section of the filter are difficult to detach from said body section without risk of damage to the drainage leaf when it is desired to remove the latter from the filter. To detach a nipple so constructed and secured, the cap nut must be first removed from the exterior end of the nipple by turning off the former from the latter by means of a suitable wrench. It has been found, however, since there is no adequate way by which to hold the nipple against turning with the cap nut, if turning of the nipple occurs, the drainage leaf will turn therewith with likelihood of abutting an adjacent drainage leaf with resultant risk of deformation of the drainage leaf structures. The hinged bottom section of the filter being open when drainage leaves are to be removed, attempts have been made to manually hold the leaf, removal of which is desired, against turning. This, however, does not avoid risk of drainage leaf deformation, but rather increases such risk, since stresses and strains are transmitted by the turning nipple to the outlet stamping of the leaf frame which are likely to distort or rupture the frame, and also likely to cause deformation of the drainage leaf from its true flat shape. Rupture of the leaf frame, if it occurs, may destroy the leaf, or, in any event, make necessary costly and laborious repair operations. Furthermore, if the drainage leaf is deformed from normal flat shape, so e. g. its faces become bulged out of normal flat plane, then proper coverage of the face areas of the drainage leaf by sluicing fluid is not obtained

2

when cleansing deposits therefrom, thus decreasing the efficiency of the drainage leaf in use.

Having the above in view, it is an object of this invention to provide an improved construction of attachment and outlet nipple for a filter drainage leaf which can be so manipulated, when demounting the leaf from the filter body, that risk of damage to the leaf is avoided. To this end, the invention provides an outlet nipple structure which is provided at its exterior end portion with means, unitary therewith, by which it can be firmly held against turning when an external fastening nut is being turned off and removed therefrom to free the nipple for withdrawal, with the associated drainage leaf, from the body of the filter.

An illustrative embodiment of this invention is shown in the accompanying drawings, in which:

Fig. 1 is a transverse sectional view of body parts to a filter in open condition, with a filter leaf attached to the stationary upper body section of the filter by means of an outlet nipple structure made according to this invention, said filter leaf and nipple being shown in elevation.

Fig. 2 is a fragmentary longitudinal sectional view of the filter leaf and outlet nipple as attached to the stationary upper body section of the filter by the novel outlet nipple structure of this invention, said view being drawn on an enlarged scale; Fig. 3 is a transverse longitudinal sectional view, taken on line 3—3 in Fig. 2; and Fig. 4 is a side elevational view of the outlet nipple per se.

Similar characters of reference are employed in the above described views, to indicate corresponding parts.

Referring to the drawings, the reference character 10 indicates the stationary upper body section of a filter, such as a filter of the leaf type, to which upper body section is pivotally connected, by hinge means 11, the movable lower body section 12 of the filter. The body sections 10 and 12 are adapted to be secured in operative closed together relation by releasable swing bolt devices 13. Integral with the top of the upper body section 10 is a longitudinally extending external boss or rib 14 which is provided with longitudinally spaced perpendicular bores 15 through which outlet nipples of the drainage leaves within the filter extend, and to which the same can be secured, whereby to support said drainage leaves in operative assembled relation to the filter body. Each bore 15 communicates through a port 16 in the side of the boss or rib 14 with suitable conduit means 17 leading to a longitudinally extending

filtrate discharge manifold 18 which is mounted on the exterior of the upper body section 10 of the filter. Mounted within the interior of the upper body section 10 is an internal manifold 19 through which, when desired, a sluicing liquid may be delivered for discharge against the surfaces of the drainage leaves, and for other purposes.

As generally constructed, a drainage leaf for use in the filter comprises a woven wire screen 20, the marginal portions of which are bound and reenforced by a sheet metal binding 21 of U-shaped cross-section, the ends of which are welded or otherwise fixedly secured to a sheet metal outlet stamping 22 which straddles the bound screen, and which is shaped for supporting connection with an internally screw-threaded outlet spud 23. Said outlet spud 23 is welded or otherwise fixed to the outlet stamping 22, and, as supported thereby, projects radially from the periphery of the drainage leaf, and so as to communicate with the interior of the latter. Over the drainage screen structure is fitted a filter cloth bag 24 upon which solids separated from the filtrate can deposit with cake forming effect as the filtrate enters and flows through the drainage leaf. To the outlet spud 23 is screwed the lower end of an outlet nipple through which filtrate can be discharged from the interior of the drainage leaf to the discharge manifold 18 of the filter.

The improved outlet nipple according to this invention comprises a cylindrical body having an axial bore open at its lower or inner end and closed at its upper or outer end. The body thus characterized can be produced in one piece as an integral casting or it can be otherwise fabricated.

For relatively inexpensive production, the nipple preferably comprises a tubular body 25 open at its lower or inner end and closed at its upper or outer end by a closure plug 26 which is inserted in the bore 27 thereof and securely affixed and sealed to the body 25, as by welding 28, so as to be unitary with the latter. Said closure plug 26 is provided with an exposed, axially projecting outer end or external head portion 29. This outer end or external head portion 29 may be variously shaped to receive application thereto of a holding implement. For example, said outer end or head portion may be of square cross-section to receive application thereto of a wrench. Preferably, however, said outer end or external head portion 29 is provided with a transverse opening 30 as shown, through which can be passed a cross bar 31 (see Fig. 2) by which holding leverage can be exerted upon the nipple to prevent turning or twisting thereof under circumstances hereinafter more fully explained. The lower end portion of the nipple body 25 is provided with an externally screw-threaded section 32, whereby it can be screwed into the outlet spud 23 of a filter leaf to be served thereby. The upper end portion of the nipple body 25 is likewise provided with an externally screw-threaded section 33, onto which can be screwed a removable fastening nut 34. Provided in the sides of the nipple body 25 are one or more filtrate discharge openings 35.

Surrounding the inner end of each bore 15 of the boss or rib 14, with which the upper body section 10 of the filter is provided, is an inner sealing gasket 36; and, similarly, surrounding the outer end of each said bore 15 is an outer sealing gasket 37.

The nipple body 25 is operatively connected to a drainage leaf by screwing the screw-threaded

section 32 of its lower or inner end into the outlet spud 23 of the drainage leaf. To assemble the drainage leaf in operative relation to and within the upper body section 10 of the filter, the lower body section 12 of the filter is released and swung down to open position (see Fig. 1), whereupon the nipple body 25 is passed upwardly through a selected bore 15 of the boss or rib 14 of said upper body section 10 until the outlet spud 23 of the drainage leaf engages the inner sealing gasket 36, and so that the upper screw-threaded section 33 of said nipple body 25 projects externally from the top of the boss or rib 14 of filter body section 10. The fastening nut 34 is thereupon screwed onto the projecting screw-threaded section 33 of the nipple body until it engages the outer sealing gasket 37. Before tightening down said fastening nut 34, a cross bar 31 is passed through the opening 30 of the head portion 29 of the nipple body, whereby leverage can be applied to said nipple body in resistance to turning thereof when the fastening nut is finally turned home into tight binding engagement with the top of the boss or rib 14 of the filter body section 10. It will be obvious that, by such manipulation, any undesirable turning or twisting of the nipple body with the turned fastening nut 34, and consequently turning or twisting of the drainage leaf, from which the nipple body extends, is prevented, so that no stresses, strains or movement of the drainage leaf, likely to involve risk of damage or injury thereto, can occur.

When the fastening nut is tightened home, the nipple body 25 is drawn axially outward relative to the bore 15 of boss or rib 14 of the filter body, so as to draw the outlet spud 23 into tight sealing engagement with the inner sealing gasket 36, while at the same time, the fastening nut 34 is thrust firmly home into sealing engagement with the outer sealing gasket 37. It will thus be apparent that not only is the drainage leaf securely assembled relative to the filter body, but also the nipple body 25 is properly sealed in connection therewith against leakage of filtrate when the filter is closed and in operation, and therefore filtrate flowing through the nipple body can only discharge by way of the openings 35, port 16 and conduit means 17 to the filtrate discharge manifold 18.

When it is desired to remove a drainage leaf from the opened filter, before turning off the fastening nut 34 from the outer end of the nipple body 25, the cross bar 31 is again passed through the opening 30 of the head portion 29 of said nipple body whereby to manually hold the latter against turning or twisting when the fastening nut is loosened for turning off from the nipple body. It will therefore be understood that again no stresses, strains or movement are transmitted to the drainage leaf likely to involve risk of injury or damage thereto.

From the above, it will be apparent that the improved nipple structure of this invention permits safe and easy manipulation of the means for fastening the same and the drainage leaf served thereby when either assembling or disassembling the latter relative to the filter, so that all risk of injury or damage to the drainage leaf structure is avoided.

Having now described my invention, I claim:

An attachment and filtrate discharge nipple for a drainage leaf of a filter apparatus of the leaf type, said nipple comprising a tubular nipple body having its lower end affixed to the outlet spud 75 of the drainage leaf for communication with the

interior of said drainage leaf and thence to withdrawably extend outwardly through a wall of the filter apparatus, said nipple body having an outlet opening in its side to communicate with the filtrate discharge means of the filter apparatus, the outer end portion of said nipple body being externally screw-threaded, a closure plug having an external diameter corresponding to the diameter of the bore of the nipple body, the lower end portion of said closure plug being entered and immovably fixed in the outer end of the bore of the nipple body as a unitary part thereof and in closing relation thereto, the upper end portion of said closure plug projecting axially outward from the nipple body so as to provide the same with an external head member of reduced diameter, a fastening nut adapted to be passed over said head member and to screw onto the externally threaded outer end portion of the nipple body for releasably securing said nipple body in operative assembled relation to said wall of the filter apparatus, said head member having a diametric transverse opening therethrough, and a cross-bar detachably engageable through said opening, said cross-bar when in place affording hand hold means for applying leverage resistance to turning move-

ment of the nipple body and therefore of the drainage leaf when tightening or loosening said fastening nut thereon, removal of said cross-bar from the head member permitting application of said fastening nut to the nipple body or withdrawal thereof therefrom.
